[57] CLAIM

The ornamental design for a luggage case, as shown and described.

DESCRIPTION

FIG. 1 is a perspective view taken from the top, front and right side of a luggage case showing our new design;

FIG. 2 is a left side elevational view thereof;

FIG. 3 is a top plan view thereof;

FIG. 4 is a front elevational view thereof, the rear being a mirror image of the front shown;

FIG. 5 is a perspective view taken from the bottom, left side thereof;

FIG. 6 is a perspective view taken from the top, front and right side of a second embodiment thereof;

FIG. 7 is a left side elevational view of FIG. 6;

FIG. 8 is a top plan view of FIG. 6;

FIG. 9 is a front elevational view of FIG. 6;

FIG. 10 is a perspective view taken from the bottom, rear and left side of FIG. 6;

FIG. 11 is a perspective view taken from the top, front and right side of a third embodiment thereof;

FIG. 12 is a left side elevational view of FIG. 11;

FIG. 13 is a top plan view of FIG. 11;

FIG. 14 is a front elevational view of FIG. 11; and

FIG. 15 is a perspective view taken from the bottom, rear and left side of FIG. 11.
